UNITED STATES PATENT OFFICE.

CHARLES G. CONN, OF ELKHART, INDIANA.

CORNET-VALVE.

Patented Sept. 29, 1914.

1,112,120.

Specification of Letters Patent.

Application filed November 11, 1913. Serial No. 800,361.

To all whom it may concern:

Be it known that I, CHARLES G. CONN, a citizen of the United States, residing at Elkhart, in the county of Elkhart and State of Indiana, have invented certain new and useful Improvements in Cornet-Valves, of which the following is a specification.

While for the purpose of illustration, I have shown my invention in connection with the finger key valves of the cornet, it will be understood that it is applicable to keys of all types of wind brass musical instruments.

Heretofore all pistons manufactured for use in valve brass musical instruments have had their bearings ground throughout their length, notwithstanding the fact that a large per cent. of the bearing between the piston and its casing might be eliminated without 10 in any way affecting the air tight bearing necessary between the piston and its casing. In instruments of this character it is only necessary that such parts of the piston valve as protect the orifices or ports through 15 the valve from leakage need have a bearing surface with the piston or valve casing. These bearing surfaces around the valve orifices or ports in the piston are absolutely necessary as otherwise the valve would leak 20 necessary and cause the instrument to play hard. Further, such leakage would be injurious to 25 the quality or volume of tone.

My invention consists in relieving the bearing surface of such parts of the valve piston from frictional contact with the valve casing as are not absolutely necessary to prevent the valve from leaking and this is done by diminishing the cross sectional area of 30 the piston at all points except through the bearing areas around the ports and at the 35 ends of the piston.

In the drawings:—Figure 1 is an elevation of a valve piston for a cornet with its casing in section; Fig. 2 is a cross sectional view on the line 2—2 of Fig. 1 showing the greater cross sectional area; Fig. 3 is a cross sectional view on the line 3—3, Fig. 1, showing the less sectional area of the piston; Fig. 4 is a vertical central section through 40 the piston on the line 4—4, Fig. 1.

The reference numeral 1 designates a finger key, 2 the piston valve carried thereby and 3 the ports or orifices formed transversely therethrough as is usual of valves of this character. At each end of the piston 45 the bearing surfaces 4 are of greater cross

sectional area than the cross sectional area of the main body of the piston. Around each port in the piston I form a bearing surface or area. The cross sectional diameter 60 of the piston through these port bearing areas or surfaces is the same as the cross sectional area through the piston at each end thereof through the bearing surfaces 4 so that the bearing surfaces around the ports 65 and the bearing surfaces at each end of the piston stand in relief with reference to the main body of the piston, whereby the frictional contact between the piston valve and the casing which usually surrounds such 70 valve is reduced to a minimum, because the only frictional bearing between the piston and its casing is with the bearing surfaces 4 at each end of the piston and the bearing surfaces or areas around the ports through 75 the piston. It has been found by experience that I can reduce the frictional contact between the valve casing and the piston valve, as above explained and as shown in the drawing, without affecting the quality 80 or volume of tone of the instrument, and at the same time, produce an instrument which is much easier to play.

I have made valves according to my invention by covering such surface of the piston 85 valve as I desire to use for a bearing surface with a gum varnish. The reduction of the diameter of the uncovered portions is then made by etching the exposed metal surface to such depth as may be deemed necessary. 90 The depth of the reduction made, however, need not be very great. The thousandth part of an inch is all that is necessary, and I believe is better than a deeper indentation. Of course, the reduction in diameter of the 95 uncovered portions of the piston can be made by a routing machine or any other tool adapted for that purpose, but I believe that the etching process gives better results.

What I claim is:—

1. A valve for brass wind musical instruments, comprising a valve casing having inlet and outlet openings for the tubing of the instrument, a piston valve having air ports to register with the said openings in the casing, bearing areas formed at the ends of the piston and bearing areas formed around said ports of the piston, whereby the piston is of the same cross sectional area at its ends and at the said bearing areas around the 110 ports, said areas forming a part of a cylindrical surface, the remaining portions of

100

110

the exterior surface being depressed below said cylindrical surface whereby the cross sectional area of the piston is less at said remaining portion than at the ends.

5 2. A finger key valve piston for brass wind musical instruments, having ports therethrough, bearing areas surrounding said ports and bearing areas at the ends of said piston, said areas forming a part of a cylindrical surface, the remaining portions of the exterior surface of the piston being

depressed below said cylindrical surface, whereby the cross sectional area of the piston at said remaining portion is less than at the said bearing areas.

15 The foregoing specification signed at Elkhart, Ind., this twenty-first day of October, 1913.

CHARLES G. CONN.
